(57) CLAIM

The ornamental design for a headboard for a bedframe, as shown and as described.

DESCRIPTION

FIG. 1 is a perspective view of a headboard for a bedframe, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof, showing the article within environment of use.

The broken lines depict portions of the headboard for a bedframe that form no part of the claimed design.

In FIG. 8, the broken lines depicting a bedframe are showing environmental subject matter that forms no part of the claimed design.

1 Claim, 6 Drawing Sheets
